HANDLE FOR A FAN

Thomas F. Helms, Chappaqua, N. Y., assignor to The Lau Blower Company, Dayton, Ohio, a corporation of Ohio

Application April 19, 1956, Serial No. 41,130

Term of patent 14 years

(Cl. D26—7)

FIG-1

FIG-2

FIG-4

FIG-3

Fig. 1 is a front perspective view of a handle for a fan embodying my new design;

Fig. 2 is a detail front elevation of the handle in Fig. 1;

Fig. 3 is a top plan view of the handle of Fig. 2; and

Fig. 4 is an end elevation of the handle of Fig. 2.

The portions shown in dotted lines in the drawing are for the purposes of illustration only.

What is claimed is:

The ornamental design for a handle for a fan substantially as shown and described.
